UNITED STATES PATENT OFFICE.

MONTAGUE MOSELEY BEAR, OF ATLANTA, GEORGIA.

GARTER.

Application filed November 29, 1926. Serial No. 151,465.

The present invention relates to improvements in garters and has for an object to provide an improved garter that will dispense with all tightness, yield ventilation and provide greater comfort.

Another object of the invention lies in providing an improved garter of simple and inexpensive construction that will be easy to apply and remove and which will be attractive and neat.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a plan view of an improved garter constructed according to the present invention.

Figure 2 is a perspective view of the garter shown in use.

Figure 3 is a rear view of the hosiery clasp.

Figure 4 is a section taken on the line 4—4 in Figure 3 with the clasp in closed position.

Figure 5 is a similar view with the clasp shown open.

Figure 6 is a cross-section taken on the line 6—6 in Figure 1; and

Figure 7 is an edge view of the cord adjusting and retaining device.

Referring more particularly to the drawings 8 designates the web of the garter which is preferably a silk band, non-elastic. This web is provided at one end with an elastic section 9 provided with the usual slide 10 for purposes of adjusting the length of the garter. The elastic section is provided with the metal fitting or clip 11 adapted to interlock with the complementary fitting or clip 12 sewed or otherwise attached to the other end portion of the web 8, which is made with the extension flap or tongue 13 adapted to lie beneath the coupled fastenings 11 and 12 and prevent the access of same to the limb, shown at 14 in Figure 2.

A flexible cord 15 is sewed at its ends 16 and 17 to end portions of the web 8 upon the obverse side and preferably adjacent the lower edge thereof, this flexible cord 15 being of greater length than the length of the web 8 between the stitched ends 16 and 17, whereby a surplus portion 18 will be pro-

vided for the purpose hereinafter described. The cord is adapted to pass through spaced casings 19 and 20 made of cloth or other appropriate material sewed to the web 8 for the purpose of guiding the cord in its longitudinal sliding movement. Between the casing 20 and the sewed end 17 is a bracket 21 sewed or otherwise affixed to the web as indicated at 22 and having the pair of slots or eyes 23 and 24 for the passage of the cord, which extends downwardly from the bracket in the loop 25 to carry the garment clasp. The eyes 23 and 24 are preferably diagonally disposed and arranged in convergent relation.

A similar bracket 26 is provided between the other casing 19 and the sewed end 16, having the diagonal convergent eyes 27 and 28 for receiving the cord and guiding the same downwardly into the loop 29, carrying the second garment fastener.

The cord is fed into and out of the loops 25 and 29 under the control of the adjusting and holding device consisting of the plate 30 sewed or otherwise secured to the web 8 between the bracket 26 and the sewed end 16 of the cord. This plate 30 is provided with the intermediate upstanding spaced ears 31 to which is pivoted the lever 32 being rounded in transverse cross-section to lie upon the cord 15 and hold it against the plate 30. The lever 32 is provided with the tooth or cam end 33 turned at substantially right angles and being disposed to the opposite side of the pivot point. This end 33 is adapted to bind upon and bite into the cord 15, forcing the cord against the plate 30 and locking it against any longitudinal movement.

The garment clasp is shown in Figures 3 to 6, inclusive, and consists of the two complementary detached or flanged clamp members 34 and 35 secured together by the pivot pin 36 for opening movement as indicated in Figure 5. The outer member 35 is provided with the projection 36' and the inner member with the tongue 37, whereby to space the flange 38 of the member 34 from the encompassing flange 39 of the larger member 35 and thus provide space to receive the thumb or finger nail of one hand, while the projection 36 is held in the other hand in the act of prying the two members apart. Moreover, the flange 38 is provided with a notch 40 which facilitates engagement of the thumb or finger nail. The tongue 37 snaps within the flange 39 which is recessed as at 39', and receives the material of the hosi-

therebetween, frictionally binding upon the same. The clasp members may be made of some material possessing more or less inherent elasticity in order to insure the binding action.

In the use of the device, the web 8 is disposed about the leg and secured by the engagement of the fastenings 11 and 12 and the hose, indicated at 41 in Figure 2, is engaged with the two clasps which will be arranged at substantially diametrically opposite points. The cord may be adjusted to provide long or short loops 25 and 29, so that the clasps may extend any desired distance below the encircling web 8. The cord may be held in the adjusting position by moving the lever 32 down against the plate 30. By swinging this lever 32 to the position shown in Figure 7, the cord 15 may be drawn longitudinally of the web 8 to either increase the amount of the surplus cord loop 18, in which case the clasps will be drawn toward the web 8; or to decrease this surplus loop 18, whereby to move the garment clasps further down from such web 8.

Suitable monograms or other embellishment may be wrought upon the garment clasps and these garment clasps may be used for other purposes, such for instance as for holding in place babies' bibs, lingerie, handkerchief holder, etc.

It will be obvious that many changes in the construction, combination and arrangement of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. An improved garter comprising a web having securing means, a flexible loose cord secured to the web, means for forming loops in the cord, means whereby said loops may be enlarged and diminished, and hosiery clasps carried by said loops of the cord.

2. An improved garter comprising a limb-

encircling band having means to secure it about the limb, a flexible cord having its ends secured to the band, means to slidably receive an intermediate portion of the cord, brackets carried by said band having eyes to receive and form loops in the cord, hosiery clasps carried by said loops, and adjusting means for the cord carried by said band for enlarging and diminishing said loops.

3. An improved garter comprising a web having securing means, a loose flexible cord secured at its ends to said web and having a surplus slack portion adjacent one end, a cord adjusting and binding device carried by the web adjacent said slack portion and comprising a plate and a lever having a cord binding portion, means carried by the web for forming loops in the cord adjustable as to length, and garment clasps carried by said loops.

4. An improved garter comprising a limb encircling web, means for securing said web about the limb, an elongated flexible cord secured fixedly at both ends to said web, guide means on the web for slidably receiving the intermediate portion of said cord, loop forming means carried on the web at opposite ends of said guide means for forming depending loops in the cord, garment clasps carried in said loops, said cord having a slack excess portion in one end portion thereof, and an adjusting device carried by the web for enabling the slack portion to be taken in or paid out, whereby to adjust the length of the loops.

5. An improved garter comprising a web, means to secure the free ends of the web about a limb, a long loose flexible cord having both ends secured to said web and having an excess slack portion in the cord near one end, means carried by the web for forming a depending loop in the cord, a garment clasp carried by said loop beneath the web, and adjusting means for engaging the excess slack portion of said cord to vary the length of the loop.

MONTAGUE MOSELEY BEAR.
